Primary Examiner—Doris V. Coles*Attorney, Agent, or Firm*—Harold H. Dutton, Jr.**[57] CLAIM**

The ornamental design for a boot guard, as shown.

DESCRIPTION

FIG. 1 is a perspective view of a boot guard showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showing of part of a boot in FIG. 1 is for illustrative purposes only and forms no part of the claimed design.
